UNITED STATES PATENT OFFICE.

EARL G. SCHWARZ, OF HIGHLAND, ILLINOIS.

PIPE-ORGAN.

1,354,853.

Specification of Letters Patent.

Patented Oct. 5, 1920.

Application filed December 15, 1916. Serial No. 137,091.

To all whom it may concern:

Be it known that I, EARL G. SCHWARZ, a citizen of the United States of America, and a resident of Highland, in the county of 5 Madison and State of Illinois, have invented certain new and useful Improvements in Pipe-Organs, of which the following is a specification.

One of the objects of this invention is to 10 provide improved means whereby the pedals pertaining to the bass pipes of pipe organs can be done away with, and the same can be operated and controlled by the keys of a piano.

15 Another object is in providing an improved solo attachment which is comprised of an electrical wiring system coöperable with the bass pipe keys of a pipe organ, in which the lowest key operated upon will 20 automatically cut out and prevent any higher note or notes from being sounded at the same time.

Other and further objects will appear in the specification, and be specifically pointed 25 out in the appended claims, reference being had to the accompanying drawings exemplifying the invention, and in which,

Figure 1 is a fragmentary plan view of a portion of a pipe organ showing the organ 30 and pedal pipes and their respective pipe chests.

Fig. 2 is an enlarged fragmentary section taken on the line II—II of Fig. 1, showing one of the two-stop actions.

35 Fig. 3 is an enlarged fragmentary section taken on the line III—III of Fig. 1.

Fig. 4 is an enlarged fragmentary section of a portion of a piano showing a portion of a mechanical player attachment applied thereto.

40 Fig. 5 is an enlarged fragmentary section taken on the line V—V of Fig. 1.

Fig. 6 is an enlarged fragmentary horizontal section taken approximately on the 45 line VI—VI of Fig. 5.

Fig. 7 is an enlarged fragmentary horizontal section taken on the line VII—VII of Fig. 4.

Fig. 8 is an enlarged section taken on 50 the line VIII—VIII of Fig. 7 showing the form of electrical contacts used in connection with the pedal keys.

Fig. 9 is a fragmentary diagrammatic view showing the improved system of electrical wiring relative to the contacts of the 55 piano keys.

Referring to the drawings, and more especially to Fig. 4, 1 designates a portion of a piano having the usual eighty-eight piano keys 2, and operably related to said keys 60 are the vertically arranged abstracts 3 that are adapted to operate the striking hammers 4 when the piano alone is being played. Located adjacent the hammers 4 is the hammer rest rail 5. Operably related to the abstracts 3 is a player operating device 6 that is controlled by the music roll 7.

Carried by each of the members 3 is a lug 8, each of said lugs being for the purpose of engaging sets of contact members such as 70 9 and 10, there being a set of said contact members 9 and 10 to each piano key 2. Leading from said contact members 9 and 10 respectively are contact wires 12 and 13, said wires leading to the pipe organ, which 75 might be located at any distance away from the piano.

Referring now to the pipe organ, arranged in said organ is a primary pressure chest 14, and located in said chest is a plurality of electromagnets 15, each of said magnets having a hollow core 16, there being a magnet 15 for each of the piano keys 2, each set of said circuit wires 12 and 13 leading to one of the magnets.

80 Operably related to the hollow core 16 of each of said magnets 15 is an armature 17, each of said armatures 17 being adapted to control an exhaust port 18. Communicating with the lower end of each of the 90 hollow cores 16 of each magnet 14, and leading therefrom to a valve-operating bellows 19 is a passageway 20, said bellows 19 being located in a secondary pressure chest 21.

Depending from each bellows 19 is a valve 95 stem 22, and carried by said stems 22 are a pair of valves 23 and 24, each of said valves 23 controlling a port 25, whereas each valve 24 is adapted to control a port 26, each set of said ports 25 and 26 communicating with 100 their respective passageways 27.

Communicating with each passageway 27 and located in said chest 21 is a valve operating bellows 28, each of said bellows 28 being adapted to operate a set of valves 29 and 30, said valves controlling ports 31 and 32 respectively. Communicating with each set of said ports 31 and 32 is a passageway 33. Leading from each of the passageways 33 are a series of tubes 34, each of said tubes 34 110 communicating with a passageway 35, in communication with a valve operating bel-

lows 36, there being a series of said bellows located in each of the stop chests 37, each of said stop chests 37 having eighty-eight pipes 38 mounted thereon, each of said pipes being 5 controlled by a set of valves 39 and 40, each of said sets of valves being controlled by one of the valve operating bellows 36, each set of said valves 39 and 40 controlling a passageway 41 which is adapted to form communication between each pipe 38 and its respective stop chest 37.

From the disclosure shown in the drawings, and in the aforesaid description, in which there are four transversely arranged 15 stop chests 37, each chest being adapted to contain eighty-eight pipes, it is to be seen that each of the piano keys 2 is operably related to four pipes, or one pipe to each of the four chests shown, although any number 20 of chests can be used in each case, as a single piano key will be capable of operating any desired number of pipes.

Mounted above the chests 37 at each end thereof is a primary valve chest 42, and a 25 secondary valve chest 43. Located in each of the chests 42 is a series of hollow cored magnets 44, each core of each of said magnets leading to a vent 45. As shown in Fig. 2, each of the chests 37 is divided by a partition 46, thereby providing a pair of compartments A and B in each chest 37, in which one set of chests 42 and 43 is related to all of the compartments A, whereas the other set of chests 42 and 43, arranged in 35 the opposite side, is related to all of the compartments B.

Leading from the upper end of each of the hollow cores of the magnets 44 is a passageway 47, each of said passageways communicating with a valve operating bellows 48, there being a plurality of said bellows 48 located in each of the valve chests 42. Each of said bellows 48 is adapted to control a set of valves 49 and 50, there being a set of 45 bellows and valves for each of the magnets 44, and there being a magnet for each of the compartments A and a magnet for each of the compartments B of each chest 37.

Leading to each set of valves 49 and 50 is 50 a passageway 51, each of said passageways communicating with a valve operating bellows 52, there being four of each of said bellows 52 located in each of said valve chests 43. Each of said bellows 52 is adapted to control an inlet valve 53, each of said valves controlling a port 54, said ports being located on the top side adjacent the ends 55 of each of the stop chests 37, and adapted to control the admission of air to thin compartments A and B.

Leading from each of the magnets 44 are circuit wires 55 and 56, said wires 56 being in communication with one of the supply wires 57, whereas said wires 55 lead to the 60 terminals 58. Operably related to each of

the terminals 58 are control terminals 59, and leading from each of said terminals 59 is a wire 60, in communication with the supply wire 61.

Referring to Fig. 3 of the drawings, 70 which discloses the control mechanism to each of the bass pipes 62, which are mounted on the bass pipe chest 63, said pipes being in communication with a horizontally arranged passageway 64 which is in communication with the chest 63 through respective ports 65. Oppositely disposed from each of said ports 65 is a port 66, said ports 65 and 66 being controlled by valves 67 and 68 respectively, each set of said valves being operated by a bellows 69, there being a series of said bellows located in the chest 63. Communicating with each bellows 69 is a passageway 70, one end of each of said passageways being in communication with a 85 hollow core 71 of a magnet 72, there being a magnet 72 for each pipe 62, said magnets being located in a chest 75. Coöperable with each core 71 is an armature 73, each armature controlling a hollow core 71 and a respective passageway 74, there being a passageway 74 for each magnet 72.

Operable with each lug 8 of each abstract 3 is an electrical contact member 76, and normally in engagement with said member 95 76 is a contact member 77. Normally held away from said contact member 76 is a contact member 78, each set of said contact members 76, 77 and 78 being coöperable with each of the pipes 62 and their respective operating mechanisms. Leading from each contact member 78 to a supply wire 79 is a wire 80, and leading from each contact member 76 of each set of bass pipe contact members to an adjacent contact member 77 is a 100 wire 81.

From an inspection of Fig. 9 it will be seen that the contact members 77 are normally in engagement with their respective adjacent contact members 76, each set of 110 contact members 76 and 77 being in communication through their respective wires 81.

In the operation of this improved device relative to the sounding of the pipes 38, assuming that current is supplied to the wires 115 12 and 13 which are coöperable with each key 2, when a number of the keys are operated, the abstracts 3 upon being elevated will cause the lugs 8 of said abstracts 3 to move the contacts 9 against respective contacts 10, thereby closing the circuits of the sets of wires 12 and 13, and the armature 17 of each magnet 15 will be drawn upwardly against its respective hollow core 16, thereby allowing the air which is in the bellows 19 to vent through its respective passageway 20 and vent 18, and since air pressure is maintained in the chest 21, said bellows 19 are collapsed and the valves 23 will be elevated from their ports 25, and at the 130

same time the valves 24 will engage their respective ports 26. This movement of said valves will place the passageways 27 in communication with the chest 21 so that the 5 air will be admitted into said passageway and into the bellows 28 that are in a receptive condition, thereby expanding said bellows and engaging the valves 29 against their respective ports 31, and at the same 10 time disengaging the valves 30 from their respective ports 32. This will allow the air from the passageways 33 to vent through the ports 32 and instantly the air which is in the passageways 35 of the stop chests 37 15 will vent, the air in said stop chests collapsing the bellows 36, thereby moving the valves 39 and 40 so that air will be admitted from the chests 37 to the passageways 41 and to their respective pipes 38, thereby 20 sounding said pipes. During the aforesaid operation, if it is desired to play the organ without sounding the piano, the hammer rest rail 5 is moved to the position shown in dotted lines in which instance the piano 25 hammers 4 will be held against the piano strings, not shown.

If it is desired to play the organ mechanically the player mechanism 6 is put into operation, in which instance the lifting members 30 83 of said mechanism 6 will cause the abstracts to be elevated instead of the piano keys 2.

It is obvious that if the piano is to be played alone, either mechanically or manually, the electric circuit relative to the contact members 9 and 10 can be deenergized.

When it is desired to operate the treble side only of any one of the chests 37, the right hand control terminal 59 is engaged 40 against its respective terminal 58, thereby closing the circuit relative to the wires 55 and 56, in which case the armature of the elected hollow cored right hand situated magnet will be drawn against the hollow 45 core thereof from against the passageway 45, thereby allowing the air to be exhausted through the passageway 47 from the bellows 48, in which instance the valves 49 and 50 will be displaced, thereby allowing the air 50 from the passageway 51 to be exhausted from the bellows 52 through the port 84, and since air pressure is carried in the chest 43, said bellows 52 will be collapsed, thereby elevating the valve 53 from the port 54 and 55 allowing air pressure to be admitted from said chest 43 to the B compartment of the elected chest 37. As shown more clearly in Fig. 7, each set of contact members 76, 77 and 78 of each pipe 62 is adapted to be 60 simultaneously operated with a set of contacts 9 and 10 of a pipe 38 as both sets of contacts will be simultaneously engaged with one of the lugs 8 which is carried by each abstract 3. Therefore it is to be seen that 65 when a piano key is operated the mecha-

nisms pertaining to a bass pipe and an organ pipe will be actuated. It is of course to be understood that only a certain number of the piano keys are coöperable with the bass pipes, in which case other keys are only 70 adapted to operate one set of contacts 9 and 10 of the organ pipes, as shown in Fig. 7.

In order to produce perfect harmony in connection with the bass pipes being played by the ordinary piano keys, it is preferable 75 to sound only one bass pipe at one time for the sounding of any desired number of organ pipes. In this connection, attention is called to Figs. 8 and 9 in which when a number of the piano keys 2 are operated, the 80 operated lugs 8 will carry the contacting members 76 against their respective contacting members 78, thereby breaking the circuit of the contact members 76 and 77. In this connection, the contacting members 85 76 and 78 will energize only one of the magnets 72, thereby allowing the contents of the bellows 69 to vent through the port 74 in which the valve 67 of the chest 63 will have moved from the port 65, while the 90 valve 68 will simultaneously close the port 66, thereby allowing air pressure to enter the passageway 64 and sound the bass pipe 62.

From the aforesaid description of the 95 circuit shown in Fig. 9, it is to be seen that all of the contacts 76 and 78 that are operated to the right of the first or lowest set of contacts 76 and 78 will be deenergized on account of its lowest contact member 76 being moved out of contact from the member 77, thereby breaking the circuit to the right of said lowest set of contacts as the lowest bass note played will automatically cut out the playing or sounding of any 100 higher bass notes. Therefore there will only be one bass note sounded at the same time that any number of organ pipe notes are sounded.

What I claim is:

1. The combination of a series of keys, a series of organ pipes and a series of bass pipes, a pair of electric circuits connecting said keys, organ pipes and bass pipes, and means adapted to be actuated by any one of 115 said keys, whereby when a number of said keys are operated together, only one of said bass pipes is sounded.

2. The combination of a series of keys, a series of organ pipes and a series of bass pipes, a pair of electric circuits connecting said keys, organ pipes and bass pipes, and means adapted to be actuated by any one of 120 said keys, whereby when a number of said keys are operated together, only one of said 125 bass pipes is sounded while the organ pipes actuated by the keys are sounded.

3. The combination of a pair of keys, a pair of bass pipes and a pair of organ pipes, an electrical circuit connecting said 130

bass pipes with said keys, and another electrical circuit connecting said organ pipes with said keys, electrical contacting members located in said circuits related to said keys and said pipes, and means provided by said contacting members whereby when said keys are operated only one of said bass pipes is sounded.

4. The combination of a series of keys, 10 a series of organ pipes and a series of bass pipes, and an electrical circuit connected to said keys and said bass pipes providing means for preventing actuation of more than one of said bass pipes when said keys are operated together while the organ pipes related to the operated keys are actuated.

5. The combination of a key, an organ pipe, and a bass pipe, an electric circuit operably related to said key and said organ

pipe, a second electric circuit operably related to said key and said bass pipe, means whereby said key controls said circuits together, and other means whereby said key controls one of said circuits independently of said other circuit. 20

6. The combination of a series of keys, a series of organ pipes and a series of bass pipes, air passageways leading to said pipes having controlling mechanisms, a pair of electric circuits related to said keys, pipes 30 and mechanisms, contacting members located in said circuits coöperable with said keys for operating the mechanisms of said pipes together, and means provided by said contacting members whereby only one of 35 said bass pipes is operated while all of said organ pipes are being operated.

EARL G. SCHWARZ.
